UNITED STATES PATENT OFFICE.

CHARLES R. JOHNSON, OF NEW HAVEN, CONNECTICUT.

DESIGN FOR A WATCH-HOLDER.

53,246.

Specification for Design.

Patented Apr. 29, 1919.

Application filed February 12, 1919. Serial No. 276,660. Term of patent 7 years.

To all whom it may concern:

Be it known that I, CHARLES R. JOHNSON, a citizen of the United States, residing at New Haven, in the county of New Haven and State of Connecticut, have invented a new, original, and ornamental Design for a Watch-Holder, of which the following is a specification, reference being had to the accompanying drawing, forming part thereof.

Figure 1 is a face view of a watch holder, showing my new design.

Copies of this patent may be obtained for five cents each, by addressing the "Commissioner of Patents, Washington, D. C."

Fig. 2 is a rear view thereof.

Fig. 3 is a perspective view of the same.
I claim:

The ornamental design for a watch holder, as shown.

CHARLES R. JOHNSON.

Witnesses:

FREDERIC C. EARLE,
C. L. WEED.
